AUTOMATIC SWITCH

Application filed May 14, 1931. Serial No. 537,250.

This invention relates to automatic switches.

Objects of this invention are to provide an automatic electric switch which is responsive to pressure variations and electrical overload conditions, which will respond to either condition an indefinite number of times, which is automatic in its action, and which may be reset when the overload condition is removed.

Further objects are to provide an automatic electric switch for controlling a motor or other device operating a pump so that a predetermined pressure may be automatically maintained, the switch opening and closing in accordance with changes in pressure without requiring any attention on the part of an operator, but which will automatically operate the same switch to hold the motor circuit open when an electrical overload occurs until the device is reset after the overload condition has been corrected, thereby providing in one and the same device an automatic control, constantly functioning under normal condition to cut the motor into and out of circuit, and also automatically functioning to cut the motor out of circuit when an electrical overload occurs, and hold the circuit open irrespective of the pressure responsive means until the device is reset by the attendant.

Further objects are to provide a compact device which, although having the characteristics enumerated above, is nevertheless simple in construction, free from delicate or easily damaged parts, and which is easy to install, and which is eminently practical in actual operation.

An embodiment of the invention is shown in the accompanying drawings, in which:

Figure 1 is a plan view of the device with the cover of the casing removed.

Figure 2 is a sectional view on the line 2-2 of Figure 1.

Figure 3 is a sectional view on the line 3-3 of Figure 1.

Figure 4 is an enlarged sectional view on the line 4-4 of Figure 3.

Figure 5 is a perspective view of the pawl of the electrical overload device.

Figure 6 is a perspective view of the guide for the pawl shown in Figure 5.

Referring to the drawings, it will be seen that the mechanism is carried within a casing or housing 1 supported by a diaphragm casing 2, the diaphragm casing housing a flexible diaphragm 3. It is preferable to provide a fitting 4 communicating with the space below the diaphragm and rigidly supporting the diaphragm casing and consequently the entire structure, so as to facilitate the simple mounting of the device. A pressure plate or pressure head 5 bears against the upper side of the diaphragm and carries three rigidly attached upwardly projecting plungers 6 which pass through the upper portion of the diaphragm casing 2 and into the housing 1. The upper ends of these posts or plungers 6 are reduced and pass through positioning washers 7 and into a lower plate 8 which supports the lower end of the main spring 9.

The spring plate 8 is provided with a plurality of upturned lugs 10 which aid in retaining the lower end of the spring in correct position, and is also provided with a pair of downwardly extending lugs 11. A main bell crank rock lever 12 is pivotally supported by the casing, as indicated at 12', and has its shorter arms pivoted to the lugs 11, as indicated at 13, see Figure 2.

A central post or stem 14 is rigidly attached to the upper portion of the diaphragm casing and is provided with a threaded upper end upon which the adjusting nut 15 is carried, such nut serving to adjust the compression of the main spring 9, a suitable washer being preferably positioned beneath the nut 15, as shown in Figure 2.

The main lever 12 is provided with a pivotally mounted link 16, which is urged downwardly by means of an adjustable spring 17. The spring 17 is preferably attached at its lower end to the main lever 12, and its upper end is attached to a threaded screw 18 provided with a nut 19 equipped with fulcrum points bearing upon the lever 16.

The free end of the link 16 is provided with a flanged roller 20, which bears upon the cam-shaped upper end of the rock lever 21, which

is pivoted intermediate its ends and which is provided with a slotted lower end. The cam face or upper portion of the rock lever 21 is triangularly shaped so as to cause the lever to rock in one or the other direction with a quick or snap action, as the roller 20 is drawn over the apex or upper end of such rock lever. This insures a quick acting mechanism which has a complete throw, although the roller 20

10 may be solely drawn across the upper end of such rock lever.

A rock plate 22 is pivoted to the casing and provided with a pin 23 which fits within the slotted end of the rock lever 21. The plate 22

15 is connected by means of a link 24 with a rocking member or lever 25. The link 24 has a slot and pin connection with the lever 25, to permit the lever 25 to be rocked to the right by overload means hereinafter described. This

20 rocking member or lever is in reality switch operating means and carries a plurality of insulating plungers 26 adjacent its upper end, which are adapted to strike the switch hereinafter described, and open such switch when

25 the switch operating means 25 is rocked in a clock-wise direction, as viewed in Figure 2.

The switch may comprise an insulating block 27 which carries a pair of switch units. Each switch unit consists of a pair of stationary contacts 28 connected, as shown in Figure 2, with the terminal members 29. A floating movable contact member 30 is loosely guided within a cavity 31 formed in the body portion 27, and is preferably provided with

35 contacts adjacent its ends adapted to engage the contacts 28 when the switch is closed. This movable contact element or switch member is biased towards closed position by means of a spring 32 socketed within the insulating body portion 27.

Any number of these switch members may be provided, two having been shown in the drawings, and each switch unit is separated from the other switch unit by the insulating body 27, preferably additional barriers 33, see Figure 1, being formed on opposite sides and between the switch members.

When the switch is opened, the switch operating means or lever 25 is rocked in a clock-wise direction, as viewed in Figure 2, and the insulating plungers 26 engage the movable contact members 30 directly in line with the springs 32 and force the contact members 30 to the right, as viewed in Figure 2, thus opening the switch. This opening motion is, of course, a snap action, as will be understood from the mechanism previously described.

The switch operating member or lever 25 is provided with an upwardly projecting arm 34, which carries a laterally projecting pin 35, see particularly Figure 1. The pin 35 loosely projects through an arcuate slot 36, see Figure 3, formed in a division wall 37 of the main casing 1.

It is to be distinctly understood that the

pressure responsive means for actuating the switch is intended in the broadest aspect of this invention to show one form of fluid condition responsive means.

This invention provides means responsive to electrical overload which also operates the same switch that is operated by the fluid condition responsive means. This electric overload device may comprise a plurality of self-soldering overload devices, such as those described in the copending application of Ivan Corcoran, Serial Number 484,694, release mechanism, filed September 26, 1930. These self-soldering devices each comprise a ratchet wheel 36, see Figures 3 and 4, which is equipped with a shaft 39 projecting into a metal block 38, solder being provided between the shaft 39 and the metal block and being adapted to melt under overload conditions to thereby allow the ratchet wheel 36 to be freely turned by means hereinafter described. The metal block 38 is clamped to a heating unit 37 carried by terminal posts 40, see particularly Figure 4. The terminal posts 40 connect with the terminal members 41, see Figure 3, to which the leads from the motor extend. It is to be noted that two of these self-soldering overload responsive means have been disclosed in the particular device chosen for illustrating this invention so that these two overload devices may be placed in two of the leads of a three-phase motor for instance, so that if any phase becomes overloaded, one or the other of the overload responsive means will operate. Obviously other circuit connections could be used provided the current flowing through the heating unit corresponded to, or in other words was proportionate to, the load carried by the motor.

The ratchet wheel 36, the block 38 and the heating unit 37 are of well known construction, and it is not believed that a fuller description is needed.

The construction of these overload self-soldering devices is identical and a description of one will therefore suffice. A pawl 42, see Figure 4, is provided with an outturned lip 43 adapted to engage and lock against one of the teeth of the ratchet wheel 36. This pawl is loosely and slidably carried by means of a simple guide 44, see particularly Figures 4, 5 and 6. The pawl may consist of a somewhat channel-shaped member provided with a tongue 44' located on the upper side of the guide 44, and with the main body portion 42 located on the under side of the guide 44, the connecting portion 45 being freely slideable within the slot 46 formed in the guide 44. It is also preferable to indent the connecting part 45 to provide a fulcrum or slideable bearing point 47, see Figure 4, engaging the wall of the slot 46 and furnishing a point about which the pawl 42 is adapted to rock. The pawl is rocked outwardly into engagement with the ratchet wheel by means of a spring

48, see Figures 1, 4 and 5, attached to the rear lip 49 of the pawl and to the upstanding forward lip or arm 50 of the guide 44, see Figures 4 and 5. The spring 48 thus serves not only to rock the pawl, but also to urge the pawl towards the right, as viewed in Figure 1.

It will be seen from reference to Figures 1 and 3 that a slide 51 preferably of insulating material is loosely guided within slots 52 formed in the arms 50 of the guides 44. This slide may have a reset handle or projecting portion 51' extending outwardly beyond the casing and adapted for manual operation to reset the device. The slide 51 is held within the slots 52 by means of a bracket 53, see Figures 1 and 3.

The slide 51 is provided with a laterally projecting arm 54, see Figures 1 and 3, which carries a plate 55 positioned in the path of movement of the pin 35 so that when the slide 51 moves to the right, as viewed in Figures 1 and 3, the projecting plate 55 will engage the pin 35 and rock the switch operating member or lever 25 in a clock-wise direction thereby opening the switch.

The construction is such that either one of the overload devices is adapted to actuate the slide 51. This is accomplished by providing the slide with a pair of shoulders 56 and 57 adapted to be engaged by the upstanding rear portion 49 of either one of the pawls, as shown in Figure 1. Thus when either pawl is released and is moved to the right, as viewed in Figure 1, by the softening of the solder restraining the corresponding ratchet wheel 36, the slide 51 will be moved to the right and will thus open the switch.

The switch remains in open position when one of the overload devices operates until the device is reset by the operator by pressing the handle or projecting portion 51, see Figure 1, inwardly. The self-soldering overload devices, of course, may operate any number of times for when the overload is removed, they are again in operative condition. However, after overload, it is necessary to manually reset the device before the switch can close.

On the other hand, the fluid condition responsive means may operate any number of times to automatically open or close the switch in accordance with the condition of the fluid. Thus there is an automatic control provided for an electric motor or similar device, which is responsive to changes in the fluid condition, such as changes in pressure for instance, and which operates intermittently and as often as required without any attention on the part of the operator, and in addition to this, automatic overload means is provided which opens the switch under overload conditions and retains the switch in open condition until reset by the operator. Both these devices operate upon the same switch and a unitary and compact mechanism is thereby secured.

The device is substantially fool-proof and is not composed of delicate, fragile or easily damaged parts, but on the other hand it has been found eminently practical in actual operation and may be used even by an unskilled operator without danger either to the apparatus or to the operator.

Further the device is simple, it may be cheaply constructed, and it may be easily installed.

Although this invention has been described in considerable detail, it is to be understood that such description is intended as illustrative rather than limiting, as the invention may be variously embodied and is to be interpreted as claimed.

I claim:

1. A control device comprising fluid condition responsive means; an electric switch normally operated by said fluid condition responsive means; and a plurality of electrical overload devices, each acting independently, for holding said switch open upon the occurrence of an electrical overload; and manual means for resetting said overload devices.

2. A control device comprising an electric switch biased towards closed position, movable means for opening said switch, pressure responsive means, link mechanism including a slotted link and a cooperating pin for normally operatively connecting said movable means and said pressure responsive means to open said switch when said pressure responsive means moves in one direction and an electrical overload device for moving said pin within said slot to open said switch when an electrical overload occurs, said electrical overload responsive device holding said pin out of operative connection with said slotted link after overload.

3. A control device comprising an electric switch biased towards closed position, movable means for opening said switch, pressure responsive means, link mechanism including a slotted link and a cooperating pin for normally operatively connecting said movable means and said pressure responsive means to open said switch when said pressure responsive means moves in one direction, an electrical overload device for moving said pin within said slot to open said switch when an electrical overload occurs, said electrical overload responsive device holding said pin out of operative connection with said slotted link after overload, a casing surrounding said switch and said pressure responsive means, and means accessible externally of said casing for resetting said electrical overload device.

4. A control device comprising an electric switch biased towards closed position, movable means for opening said switch, said movable means having a projecting pin, pressure responsive means, link mechanism including a slotted link receiving said pin and cooper-

- ating with said pin for movably connecting said movable means and said pressure responsive means to open said switch when said pressure responsive means moves in one direction, a slide bar having means arranged in
5 the path of the movement of said pin, and a plurality of thermally operable electrical overload devices, each adapted to independently move said slide bar to engage said pin and open said switch.
10 In testimony whereof, the signature of the inventor is affixed hereto.

HERMON L. VAN VALKENBURG.
